BURNER SUPPORT FOR OPEN HEARTH FURNACES

Charles J. Barkley, Orem, Utah, assignor to United States Steel Corporation, a corporation of New Jersey

Application January 19, 1953, Serial No. 332,008

6 Claims. (Cl. 263—15)

This invention relates to a burner support for open hearth furnaces for producing steel. Such furnaces are of the regenerative type and in many instances have a burner located at each end of the furnace on the center line thereof between two ports or uptakes. The conventional support for the burners includes two vertical refractory walls supported by a refractory sprung arch. Normally, a second or wearing arch is provided to protect the first arch from damage due to heat, velocity of the gases and erosion. When the arches erode and fail it is necessary to shut down the furnace. Other disadvantages due to this type of support include inaccessibility for minor repairs, air leakage and restricted gas flow due to the large mass of brick work required.

It is therefore an object of my invention to provide a burner support which is readily accessible and which eliminates the need of a sprung supporting arch.

This and other objects will be more apparent after referring to the following specification and attached drawings, in which:

Figure 1 is a sectional plan view of an open hearth furnace showing the arrangement of the burners;

Figure 2 is an enlarged view of a portion of Figure 1 showing the burner support at one end of the furnace;

Figure 3 is a sectional view taken on the line III—III of Figure 2; and

Figure 4 is a sectional view taken on the line IV—IV of Figure 3.

Referring more particularly to the drawings, the reference numeral 2 indicates an end of an open hearth furnace. A plurality of buckstays 4 are arranged at the end of the furnace in spaced apart relationship. A burner 6 is arranged on the longitudinal center line of the furnace. The uptake from the checker chambers is divided into two passageways 8 by means of a central burner support 10, commonly called the dog house. The support for the dog house consists of a pair of spaced apart channels 12 and a second pair of spaced apart channels 14 arranged above the channels 12. One end of each of the channels 12 and 14 is attached to the buckstays 4 by means of angles 15 and the other end is attached to a chill diaphragm or support 16. The two lower channels 12 serve as a support for a suspended arch 18. Vertical hangers 20 extend between and are supported by channels 12 and 14 and are provided with lintels 22 for supporting the side walls 24 of the dog house. Vertical supports 26 extend upwardly from and are supported by each channel 14. The support 26 supports a cooler 28 for the burner. Lintels 30 on the supports 26 also serve to support the walls 24. A refractory wall 32 connects the wall 24 at the top thereof. The opening provided by the arch 18, the walls 24 and cooler 28 or wall 32 is of such size that a workman may easily enter from the outside of the furnace in order to repair the refractory or seal it from air infiltration.

While one embodiment of my invention has been shown and described it will be apparent that other adaptations

2

and modifications may be made without departing from the scope of the following claims.

I claim:

- 5 1. In an open hearth furnace having a plurality of buckstays at one end, a chill structure spaced inwardly from the end of said furnace, an uptake from the regenerative chamber between the end of the furnace and the chill structure, and a burner supporting structure dividing said uptake into two passageways; the improvement comprising a box-like metallic liner burner supporting structure having one end connected to said buckstays and the other end connected to said chill structure, a refractory arch suspended from the bottom of said box-like metallic supporting structure, a vertical refractory wall fastened to each side of said box-like metallic supporting structure, and a refractory wall connecting the tops of said vertical refractory walls.
- 10 2. In an open hearth furnace having a plurality of buckstays at one end, a chill structure spaced inwardly from the end of said furnace, an uptake from the regenerative chamber between the end of the furnace and the chill structure, and a burner supporting structure dividing said uptake into two passageways; the improvement comprising a hollow box-like metallic liner burner supporting structure having one end connected to said buckstays and the other end connected to said chill structure, a refractory arch suspended from the bottom of said box-like metallic supporting structure, a vertical refractory wall fastened to each side of said box-like metallic supporting structure, and a refractory wall connecting the tops of said vertical refractory walls, the opening in said box-like metallic supporting structure being of sufficient size to enable a workman to pass therethrough, said opening being open to the outside of said furnace.
- 15 3. In an open hearth furnace having a plurality of buckstays at one end, a chill structure spaced inwardly from the end of said furnace, an uptake from the regenerative chamber between the end of the furnace and the chill structure, and a burner supporting structure dividing said uptake into two passageways; the improvement comprising bottom structural members having one end connected to said buckstays and the other end connected to said chill structure, top structural members having one end connected to said buckstays and the other end connected to said chill structure, said top and bottom structural members forming a liner, a refractory arch suspended from the bottom structural members, a vertical refractory wall on each side of said structural members fastened thereto, and a refractory wall connecting the tops of said vertical refractory walls.
- 20 4. In an open hearth furnace having a plurality of buckstays at one end, a chill structure spaced inwardly from the end of said furnace, an uptake from the regenerative chamber between the end of the furnace and the chill structure, and a burner supporting structure dividing said uptake into two passageways; the improvement comprising bottom structural members having one end connected to said buckstays and the other end connected to said chill structure, top structural members having one end connected to said buckstays and the other end connected to said chill structure, said top and bottom structural members forming a liner, a refractory arch suspended from the bottom structural members, a vertical refractory wall on each side of said structural members fastened thereto, and a refractory wall connecting the tops of said vertical refractory walls.
- 25 5. In an open hearth furnace having a plurality of buckstays at one end, a chill structure spaced inwardly from the end of said furnace, an uptake from the regenerative chamber between the end of the furnace and the chill structure, and a burner supporting structure dividing said uptake into two passageways; the improvement comprising bottom structural members having one end connected to said buckstays and the other end connected to said chill structure, top structural members having one end connected to said buckstays and the other end connected to said chill structure, said top and bottom structural members forming a liner, a refractory arch suspended from the bottom structural members, a vertical refractory wall on each side of said structural members fastened thereto, and a refractory wall connecting the tops of said vertical refractory walls, the opening defined by said top and bottom and refractory walls being open to the outside of said furnace.
- 30 6. In an open hearth furnace having a plurality of buckstays at one end, a chill structure spaced inwardly from the end of said furnace, an uptake from the regenerative chamber between the end of the furnace and the chill structure, and a burner supporting structure dividing said uptake into two passageways; the improvement comprising bottom structural members having one end connected to said buckstays and the other end connected to said chill structure, top structural members having one end connected to said buckstays and the other end connected to said chill structure, said top and bottom structural members forming a liner, a refractory arch suspended from the bottom structural members, a vertical refractory wall on each side of said structural members fastened thereto, and a refractory wall connecting the tops of said vertical refractory walls, the opening defined by said top and bottom and refractory walls being open to the outside of said furnace.
- 35 7. In an open hearth furnace having a plurality of buckstays at one end, a chill structure spaced inwardly from the end of said furnace, an uptake from the regenerative chamber between the end of the furnace and the chill structure, and a burner supporting structure dividing said uptake into two passageways; the improvement comprising bottom structural members having one end connected to said buckstays and the other end connected to said chill structure, top structural members having one end connected to said buckstays and the other end connected to said chill structure, said top and bottom structural members forming a liner, a refractory arch suspended from the bottom structural members, a vertical refractory wall on each side of said structural members fastened thereto, and a refractory wall connecting the tops of said vertical refractory walls, the opening defined by said top and bottom and refractory walls being open to the outside of said furnace.

tive chamber between the end of the furnace and the chill structure, and a burner supporting structure dividing said uptake into two passageways; the improvement comprising a pair of channels spaced apart transversely of the furnace, means for fastening one end of each of said channels to said buckstays, means for fastening the other end of each of said channels to said chill structure, a second pair of channels spaced apart transversely of the furnace above the first pair of channels, means for fastening one end of each of said last named channels to said buckstays, means for fastening the other end of each of said last named channels to said chill structure, a refractory arch suspended from the first pair of channels, vertical structural members fastened to at least one pair of said channels and extending between said channels and above the top channels, a pair of vertical refractory walls each supported by said vertical structural members on the outside of said channels, and a refractory wall connecting the tops of said vertical refractory walls.

6. In an open hearth furnace having a plurality of buckstays at one end, a chill structure spaced inwardly from the end of said furnace, an uptake from the regenerative chamber between the end of the furnace and the chill structure, and a burner supporting structure dividing said uptake into two passageways; the improvement comprising a pair of channels spaced apart transversely of the furnace, means for fastening one end of each of said channels to said buckstays, means for fastening the other

end of each of said channels to said chill structure, a second pair of channels spaced apart transversely of the furnace above the first pair of channels, means for fastening one end of each of said last named channels to said buckstays, means for fastening the other end of each of said last named channels to said chill structure, a refractory arch suspended from the first pair of channels, vertical structural members fastened to at least one pair of said channels and extending between said channels and above the top channels, a pair of vertical refractory walls each supported by said vertical structural members on the outside of said channels, and a refractory wall connecting the tops of said vertical refractory walls, the opening defined by said channels and refractory walls being of sufficient size to enable a workman to pass therethrough, said opening being open to the outside of said furnace.
